INVENTOR.

UNITED STATES PATENT OFFICE.

HERBERT ALFRED LUCAS BARRY, OF WESTMINSTER, ENGLAND.

WINCH.

SPECIFICATION forming part of Letters Patent No. 715,742, dated December 16, 1902.

Application filed July 18, 1901. Serial No. 68,822. (No model.)

To all whom it may concern:

Be it known that I, HERBERT ALFRED LUCAS BARRY, a subject of the King of Great Britain and Ireland, residing at 15 Great 5 George street, in the city of Westminster, England, have invented a new and useful Improved Winch Applicable for Use in Connection with Means for Transporting Materials, (in respect whereof I have applied for 10 a patent in Great Britain, to bear date June 15, 1901, No. 12,243,) of which the following is a specification.

This invention relates to an improved method of constructing and working winches, 15 more particularly, though not exclusively, adapted for employment with transporters of the type wherein two ropes are employed, the one for lifting and lowering as well as for traveling the load and the other for traveling 20 the carriage and load, the objects of the present invention being to render such winches incapable of free action while effecting the change from one position to another of the clutch and to provide means for driving the drums at a relatively different speed. 25

Friction-winches as ordinarily constructed and wherein the winding-drum is alternately clutched with the driving mechanism or with means for holding it stationary have proved 30 unsatisfactory and often dangerous, owing to the fact that during the coupling or uncoupling of the parts of the clutch there occurs an interval when the drum is capable of being 35 revolved, owing to the part being under the strain of the load. Where any but exceptionally light loads are concerned, this free action constitutes a serious objection.

In the accompanying drawings, Figure 1 is a longitudinal section of the improved winch. 40 Fig. 2 is an elevation of the right-hand end of Fig. 1. Fig. 3 is a plan of the gearing employed for driving the drums, whereby their speed of rotation is rendered relatively different.

In constructing a winch according to my improved method and applied, by way of example, in connection with a transporter wherein two ropes are employed, the one for lifting and lowering as well as for traveling the load 45 and the other for traveling the carriage and load, I mount upon a shaft A a pair of drums B and C, each drum being capable of rotating

freely thereon and both drums being normally capable of joint rotation by means of a friction-coupling, whereof the part b is carried by the drum B and the part c by the drum C. The parts b and c are formed as annular rings, with conical contact-surfaces. A peripheral covering of wood may be applied to the part b, as shown, for increasing the grip between the parts. One of the drums (in the example illustrated C) is free to move laterally on the shaft, while the other, B, is held against lateral movement by its boss b', which extends in the form of a neck through the bearing D pertaining to that end of the shaft and is furnished with a collar b² outside the bearing. The laterally-movable drum C is maintained in frictional contact with the drum B by means of a spiral opening c', whereof one end is carried by a sleeve a, mounted loosely on the shaft A and abutting against the adjacent bearing D', the other end of the spring taking its bearing against the inner side of the boss c² of the drum C. Fast on the shaft and between the drums is a friction-disk E, the coned surface e whereof is arranged to engage a coned surface c², with which the annular ring c pertaining to the laterally-movable drum C is provided. Upon imparting a longitudinal movement to the shaft A, which in the construction illustrated is effected by the forked lever F through the instrumentality of the lever F' and connecting-rod F², the disk may be put into or out of frictional contact with the laterally-movable drum. The fork f of the lever F embraces the shaft A between collars a' a', the lever being fulcrumed at f' in the bracket or support f². The lever F' works over a setting-quadrant F³, a bolt F⁴ on the lever engaging with teeth f³ on the said quadrant. Upon the shaft A is mounted a worm-wheel C', which is capable of sliding upon the shaft by means of a feather and feather-way. The worm-wheel is driven by a worm C², the latter being rotated by a bevel-wheel C³ on the worm-shaft C⁴ meshing with a bevel-wheel C⁵ on the shaft C⁶, which is driven from the engine. The laterally-held drum B is furnished with a spur-wheel B', with which meshes a spur-pinion B², driven by the engine. The worm C² may be rendered operative by means of a clutch C⁷, the latter being controlled or worked by a le-

ver C⁸ in connection, by means of the link C⁹, with the lever C¹⁰ pertaining to the movable part of the clutch.

In working a transporter with the aid of the improved winch, assuming the laterally-movable drum C to be moved out of engagement with the laterally-held drum B and the disk E on the shaft A to be in engagement with the drum C, the shaft will be held stationary by the worm-gear C' C². Consequently the laterally-movable drum C cannot rotate. The drum B is, however, free to be rotated by the spur-gearing B' B², so as to lift or lower the load. In order to put into operation dumping mechanism of the type wherein the return-block carries a hook which is arranged so as to move vertically in relation to the block-casing, a plunger which is in mechanical connection with the said casing being so arranged that upon the motion of the carriage being reversed the said plunger operates a trigger-lever carried by the bridle of the bucket and releases the latter, two ropes being employed for manipulating the carriage and the load, it is necessary to slowly wind the rope on the laterally-movable drum C, while (in lowering the load) the rope is paid out faster from the drum B. This is accomplished by rendering the clutch C⁷ operative, the worm C² thereupon effecting the rotation of the worm-wheel C', the disk E and drum C rotating therewith. When it is desired to travel the load, the disk E is moved away from the drum C by pulling over the lever F', and thereby imparting a longitudinal movement to the shaft A, with the result that during the receding of the disk E the drum C follows by means of the pressure exerted thereon by the spring c', and so maintains engagement between the surfaces c^x and e until the parts of the coupling upon each drum—i. e., the surfaces b and c—become engaged, when the disk E, completing its lateral movement, becomes disengaged from the drum C. Both drums are now in engagement by means of the friction-coupling b c, the driving of the drum B effecting the simultaneous rotation of the drum C and, as the case may be, winding or paying out the respective ropes at an equal pace.

From the foregoing it will be apparent that there is no point at which the laterally-movable drum C is uncoupled from the drum B and at the same time out of contact with the friction-disk E.

By the employment of suitable gearing the shaft A and disk E may be rotated in the opposite direction to that of the spur-wheel B'.

Under these circumstances the laterally-movable drum C would be rotated in the same direction as the spur-wheel B' or in the direction of the disk E.

By directly connecting one part of the friction-coupling—for example, the part b—with the spur-wheel B' the arrangement may be adapted for employment as a single-drum winch.

What I claim as my invention, and desire to secure by Letters Patent, is—

1. A winch constructed substantially as herein described and comprising a shaft having mounted thereon a pair of drums whereof one is movable in a lateral direction, by means of a coupling-disk mounted on the said shaft and intermediate the drums whereby the latter are put into and out of operation so as to act conjointly or separately without free action of the winch while changing the coupling-disk from one position to another, substantially as set forth.

2. A winch constructed substantially as herein described and comprising a shaft, a pair of drums mounted on said shaft and whereof one is movable laterally, a coupling-disk also mounted on said shaft between the drums, means for operating the disk and the laterally-movable drum whereby the drums are rendered capable of joint or of separate operation, without permitting free action while effecting the change from one position to another of the disk, and means for driving the drums at a relatively different speed, substantially as set forth.

3. In a winch, the combination, with a shaft A, of a drum B loosely mounted thereon and a drum C also mounted on the said shaft but laterally movable thereon, coupling-disk E engaging one or both the drums, a spring c', levers F, F' for operating the shaft and the disk E, and spur-gearing B', B², substantially as and for the purposes specified.

4. In a winch, the combination, with a shaft A, of drums B, C, respectively formed with frictional surfaces b, c, spring c', coupling-disk E, levers F, F', spur-gearing B', B², worm-gearing C', C², and clutch C⁷ all arranged and operating substantially as and for the purposes specified.

In testimony whereof I have signed my name to this specification in the presence of two subscribing witnesses.

HERBERT ALFRED LUCAS BARRY.
